UNITED STATES PATENT OFFICE.

WALTER P. MURPHY, OF CHICAGO, ILLINOIS, ASSIGNOR TO P. H. MURPHY COMPANY, OF PARNASSUS, PENNSYLVANIA, A CORPORATION OF PENNSYLVANIA.

CAR-ROOF.

1,227,484.

Specification of Letters Patent.

Patented May 22, 1917.

Application filed November 17, 1913. Serial No. 801,462.

To all whom it may concern:

Be it known that I, WALTER P. MURPHY, a citizen of the United States, residing at Chicago, in the county of Cook and State 5 of Illinois, have invented certain new and useful Improvements in Car-Roofs, of which the following is a specification.

The object of my invention is to provide an efficient all metal load sustaining car 10 roof, for steel frame cars, which is of such construction that the movements of the car body in transit will not impose any twisting or warping strains on the roof.

My invention consists of a car roof comprising a skeleton frame, load sustaining metallic roofing sheets spanning the open spaces of said frame and supported thereon, said sheets having corrugations extending lengthwise thereof, the corrugations of the 20 side marginal portions of adjacent sheets overlapping and interlocking, and locking means passing through the overlapped marginal portions and anchored to the car and to said frame, whereby the sheets are secured together and to the car. My invention further consists of the parts and combination of parts as will be more fully hereinafter pointed out.

In the drawings:

Fig. 1 is a top plan view of a car roof, portions being broken away;

Fig. 2 is an end view of the same with portions broken away;

Fig. 3 is a section on the line B—B, Fig. 1;

Fig. 4 is a section on the line A—A, Fig. 1;

Fig. 5 is an enlarged detail section through the joint between the roofing sheets at the ridge;

Fig. 6 is a top plan view of the seam supported;

Fig. 7 is a front elevation of the same;

Fig. 8 is a top plan view of a carline;

Fig. 9 is a side elevation of the same.

The reference numeral 1 designates a side 45 plate formed of angle iron to one portion of which the side walls of the car are suitably secured in any approved manner. The carlines 2 are formed from T iron and extend from eaves to eaves of the car and have

50 downwardly turned ends 3 which are secured to the side plates by means of the rivets 4.

The head of the carlines is deflected upward as at 5 leaving flat intermediate portions or purlin seats 6, said seats having suitable bolt openings for the purlin bolts. The upstanding portions 5 constitute strengthening members for the carlines.

The purlins 7 are rigidly secured on top of the carlines in the seat 6 by means of suitable bolts or rivets 8. The ridge pole 8^a 60 is provided with an enlarged seat 9 on the carlines.

The end plate 10 is of angle iron, one member of which is bolted to the ridge pole and as a further tie I provide another angle iron 65 11 secured to the end plate and extending under the ridge pole and terminating in an upstanding end 12 which enters a groove or recess formed in the underface of the ridge pole. 13 are bolts securing the angle iron 70 11 to the ridge pole; one of said bolts also passing through one member of the end plate. 14 is a fascia on the ends of the car to which the bracket 15 for the running board is secured.

The roofing sheets 16 are load sustaining sheets extending from eaves to eaves and are constructed of corrugated metal, the side marginal portions of adjacent sheets overlapping and interlocking as shown in 80 one of the enlarged detail views.

17 are supporting blocks secured to the ridge pole in position to fit in one of the corrugations and underlie the overlapped portions of the roofing sheets, a bolt 18 85 passing through the ridge pole, said supporting block and the overlapped portions of the roofing sheets, whereby the roofing sheets are secured at the ridge to the roof frame. These bolts 18 also 90 pass through the running board saddle 19, which has a concaved underface conforming to the corrugations of the roofing sheets. 20 is a cap which fits over the saddle 19 to cover the bolt 18 and the hole in 95 the saddle against the weather; said cover having side marginal depending flanges 21 which fit on each side of the saddle. The running boards 23 are suitably secured to the saddles 19.

The end roofing sheets 24 at their outer side marginal edge are bent downwardly

over the fascia as shown in one of the enlarged detail views, and a flashing 25 is secured to the fascia and provided with a corrugated hood portion constructed to interlock on top of the car with the corrugations of the end sheet and form therewith a weather proof joint, the end running board saddle fitting over said overlapped portions.

26 are sheet supports which are secured 10 at proper intervals to the eaves purlins 7* which fit within a corrugation of the overlapped side marginal portions of the load sustaining roofing sheets at the eaves and underlie the overlapped joint between the 15 sheets as shown in the drawings. These sheet supports 26 have base flanges 27 provided with suitable bolt openings, whereby their supporting members are secured to the eaves purlins 7*. The sheet support 26 is 20 provided with an undercut groove 28 in its upper face having an inclined bottom 29 divided into a series of drains by means of the ribs 30, said groove having a stop 31 to prevent a bolt seated therein from slipping outward beyond a certain limit. The 25 top of the sheet support 26 is sloped to agree with the arch or angle of the load sustaining roof sheets. 32 is a drip apron integral with the support 26 and spaced 30 from the eaves of the car and substantially U shaped in cross section. This apron 32 serves as a spacer for the metal eaves cap 33.

The eaves cap 33 is flat throughout its 35 length and substantially L shaped in cross section and extends the full length of the car at the eaves. The hood portion 34 of said cap overlying the eaves end of the load sustaining roofing sheets is secured thereto by means of the bolts 35, the heads of which 40 are secured in the undercut groove 28 of the eaves sheet supports, 26, said bolts passing through the overlapped side marginal portions of the load sustaining roofing sheets at their eaves end, thereby holding 45 the sheets down at the eaves. The apron portion of the eaves cap overhangs the eaves and extends below the joint between the load sustaining roof sheets, and the eaves purlins, and side plate, thereby weatherproofing said joints; said apron being 50 spaced laterally from the side plate by the spacer 32 of the eaves sheet support 26. The hood being flat throughout its length offers no obstruction to rain, snow, etc., 55 passing freely off of the roof at the eaves.

The apron of the cap extending down past the eaves end of the roof sheets prevents rain, snow, etc., from being blown into the car through the openings above 60 the side plate made by the corrugations of the roof sheet.

The flat portion of the hood 33 on top of the roof sheets acts as a securing strip

to hold the roof sheets to the car between the seam fastenings, and to prevent the 65 roof sheet from buckling between the seams, due to the upward pressure exerted by air currents on the underface of the roof sheets as the air passes through the spaces formed by the corrugations above the side plate, 70 said spaces serving as ventilators between the roof sheets and the side plate thereby preventing condensation or sweating on the underface of the roof sheets.

If, by accident, rain, etc., should follow 75 the bolt 35, it is drained therefrom through the inclined drain 29 and discharged at the eaves of the roof.

The stop 31 serves to prevent the bolts 35 from working out of the supports 26 80 in the event of the nut thereof becoming loosened and lost.

36 is a roof hand hold and 37 are wooden slats secured on the roof as required by the 85 safety appliance laws.

From the above description it will be understood that a roof constructed in accordance with my invention is adapted to withstand the weaving movements of a car incident to travel and at the same time 90 remain weather proof.

What I claim is:

1. A car roof including a skeleton frame, corrugated roof sheets spanning the open spaces of the frame, the corrugations extending the full length of the sheet, and an eaves member comprising a flat strip secured on top of the roof sheets, said sheets being secured against movement longitudinally of said strip, and an apron extending from the strip down past the eaves end of the roof sheets, said apron being spaced from the car throughout its length. 95

2. A car roof including a skeleton frame, a series of load sustaining corrugated roof sheets spanning the open spaces of the frame, the corrugations of the roofing sheets permitting free ventilation over the sides of the car beneath the roof sheets, a combined eaves cap and fascia comprising a horizontal body arranged across the eaves ends of the roofing sheets and fastened to the top of the car to secure them in place, and a vertical apron forming a fascia depending down alongside of the car with its lower edge free and spaced from the car, said apron extending down past the eaves ends of the roofing sheets and spaced therefrom to permit such ventilation of the undersides of the sheets. 10

3. A car roof including a skeleton frame, corrugated roof sheets spanning the open spaces of the frame, the corrugations extending the full length of the sheets, said sheets overlapping at their side marginal portions, an eaves flashing and securing 11

means comprising a flat strip secured on top of the roof sheets along their eaves ends, said sheets being secured against movement longitudinally of said strip, and 5 an apron extending from the strip down past the eaves end of the roof sheets, said apron being spaced from the car throughout its length, and securing means passing through the flat strip and roof sheets at 10 the overlapped joints thereof; said eaves flashing strip acting to hold the roof sheets to the car between the said fastening means and to prevent the sheets from buckling between the fastening means due to the 15 upward pressure exerted by air currents on the under face of the said sheets.

4. A car roof comprising a skeleton frame, load sustaining rigid metallic roofing sheets spanning the open spaces of said 20 frame and supported thereon and secured thereto, said sheets having corrugations extending lengthwise thereof at their side marginal edges, the corrugations of adjacent sheets overlapping, an eaves member 25 secured to the side plate beneath the overlapping corners of said sheets and extending inwardly in a corrugation of the overlapped joint between the sheets, and a bolt anchored to said eaves member and passing 30 upwardly through the overlapped side marginal edges securing them together and to the eaves member.

5. A car roof comprising a skeleton frame, load sustaining metallic roofing sheets spanning the open spaces of said 35 frame and supported thereon and secured thereto, said sheets having corrugations extending lengthwise thereof at their side marginal edges, the corrugations of adjacent 40 sheets overlapping, an eaves member secured to the side plate and extending inwardly in a corrugation of the overlapped joint between the sheets, a bolt anchored to said eaves member and passing upwardly 45 through the overlapped side marginal edges securing them together and to the eaves member, said member having a water shed extending from said bolt to the eaves of the car.

50 6. A car roof comprising a skeleton frame, load sustaining rigid metallic roofing sheets spanning the open spaces of said frame and supported thereon and secured thereto, corrugations extending lengthwise 55 of the sheets at their side marginal edges, the corrugations of adjacent sheets overlapping, and a locking means passing through the overlapped marginal edges and anchored to the top of the car within the lines 60 of the car body, whereby the sheets are secured together and to the car and a fascia covering the open ends of said corrugations and extending above the eaves and overlying

ing the eaves end portions of the roofing sheets and secured to the sheets by said locking means. 65

7. A car roof comprising a skeleton frame, load sustaining rigid metallic roofing sheets spanning the open spaces of said frame and supported thereon and secured thereto, corrugations extending lengthwise of the sheets at their side marginal edges, the corrugations of adjacent sheets overlapping, and a locking means passing through the overlapped marginal edges and anchored to the car whereby the sheets are secured together and to the car, and an angle fascia having one flange spaced from the eaves and free of the side of the car and its other flange extending over the eaves and on top of the car and overlying the eaves end portions of the roofing sheets and secured to the car by said locking means. 75

8. An all steel car roof comprising a series of corrugated sheets the side margins 85 of the adjacent sheets overlapping along the side marginal edges thereof, a fascia secured to the top of the car and extended down past the eaves end of the sheets, said extended portion being spaced from and 90 free of the car throughout its length.

9. A car roof comprising a plurality of roofing sheets overlapping each other at their side marginal edges, a fascia extended on top of the roof sheets and means securing 95 the roof sheets at their overlapped side marginal edges together and to the extended portion of the fascia on top of the car and within the lines of the car body.

10. A car roof comprising a plurality of 100 corrugated sheets, the side marginal corrugations of which overlap each other, a filler block secured to the car frame and extending inward from the eaves in a corrugation of the overlapped side marginal edges of the 105 roof sheets, means securing said overlapped edges of the sheets together and to the filler block; said filler block having an upper portion to receive the fastener and a lower portion spaced therefrom to constitute a water 110 drain extending to the eaves.

11. In a car roof having corrugated sheets, an eaves member having an inwardly extending portion constructed to pass under the roof sheets and lie in a corrugation 115 thereof, said member having an undercut groove in its top surface extending inwardly from the eaves, said groove constituting a water drain and an anchoring medium for a roof bolt. 120

12. A car roof comprising a skeleton frame, load sustaining corrugated metallic roofing plates spanning open spaces of said frame and having their side marginal corrugations overlapped, an eaves member 125 comprising a body constructed to fit with

- in a corrugation on the underface of the lapped joint of the sheets, a spacing element on the eaves end of said member and a flange depending from the underface of said member constructed to be secured to the car body structure, a bolt secured to said member and passing through the lapped joints of the roofing sheets, a water shed formed in said body and extending from 5 the said bolt to the eaves, and a fascia spaced from the eaves end of the roofing sheet by said spacing element and extending on top of the eaves portion of the roofing and secured thereon by means of said bolt.
- 10 13. An eaves fastening and support for a hollow seam car roof comprising a base flange, a sheet support provided with an undercut groove in its upper portion having an inclined bottom to draw moisture to the 15 eaves of a car; said groove being adapted to receive a roof fastening bolt, a stop in said groove to limit the outward movement of said bolt, and a drip apron depending from the outer end of said support, said 20 apron also serving to space a fascia from the side wall of a car.
14. An eaves fastening and support for a hollow seam car roof comprising a base flange, a sheet support constructed to enter 25 a hollow seam, and provided with an undercut groove in its upper portion having an inclined bottom, ribs dividing said bottom into a series of drains, said groove being adapted to receive a roof fastening bolt, 30 a stop in said groove to limit the outward movement of said bolt, and a drip apron depending from the outer end of said support, said apron also serving to space a fascia from the side of a car.
- 35 15. A car including a skeleton frame, corrugated roof sheets spanning open spaces of the frame and having corrugations extending the full length of the sheets, an eaves member comprising a flat strip secured on 40 top of the roof sheets over the corrugations at the eaves of the car, and having a depending portion extending down opposite the eaves ends of the roof sheets and spaced therefrom, and fastening means for said 45 roof sheets and strip having a projecting portion for spacing said depending portion of the eaves member away from the side of the car, said fastening member having means for holding said roof sheets and 50 eaves strip against relative longitudinal movement along the eaves of the car.
- 55 16. An all-steel car roof comprising a series of corrugated sheets, the side margins of adjacent sheets overlapping and forming 60 loose joints, a fascia secured to the top of the car over the ends of said corrugated sheets, said fascia having a depending portion extending down past the eaves ends of the car side throughout its length, and fastening means for said roof sheets and fascia, said fastening means having portions arranged in the corrugations of the roof sheets and outwardly projecting portions for spacing said depending portion of the fascia away from the side of the car, said outwardly projecting portions of the fastening means depending in spaced relation to the side of the car.
17. A car including a skeleton frame, corrugated roof sheets spanning open spaces of the frame and having corrugations extending the full length of the sheets, an eaves member comprising a flat strip secured on top of the roof sheets over the corrugations at the eaves of the car, and having a depending portion extending down opposite the eaves ends of the roof sheets and spaced therefrom, and fastening means for said roof sheets and strip having a projecting portion for spacing said depending portion of the eaves member away from the side of the car, and said projecting portion itself depending in spaced relation to the side of the car, said fastening member having means for holding said roof sheets and eaves strip against relative longitudinal movement along the eaves of the car.
18. An all steel car roof comprising a series of corrugated sheets, the side margins of adjacent sheets overlapping and forming loose joints, a fascia secured to the top of the car over the ends of said corrugated sheets, said fascia having a depending portion extending down past the eaves ends of said sheets and spaced therefrom, said depending portion being free of the car side throughout its length, and fastening means for said roof sheets and fascia, said fastening means having portions arranged in the corrugations of the roof sheets and outwardly projecting portions for spacing said depending portion of the fascia away from the side of the car, said outwardly projecting portions of the fastening means depending in spaced relation to the side of the car.
19. A car roof comprising roof sheets having corrugations extending transversely of the car at the eaves, fascia strips arranged over the eaves ends of said roof sheets and having depending portions spaced from the side of the car, eaves fastenings projecting inwardly from the eaves and arranged in said corrugations, and bolts held by said eaves fastenings, said bolts projecting up through said roof sheets and fascia strips and having means on their upper ends for securing said roof sheets and fascia strips in place.
20. A car roof comprising roof sheets having corrugations extending transversely of the car at the eaves, fascia strips arranged

over the eaves ends of said roof sheets, eaves fastenings projecting inwardly from the eaves and arranged in said corrugations, bolts held by said eaves fastenings, said 5 bolts projecting up through said roof sheets and fascia strips and having means on their upper ends for securing said roof sheets and fascia strips in place, and means arranged beneath said bolts and extending

over the eaves for draining water which 10 passes through said roof sheets at the bolts off of the eaves.

In testimony whereof I affix my signature in presence of two witnesses.

WALTER P. MURPHY.
